UNITED STATES PATENT OFFICE.

FRANK S. WEAVER, OF BELLEVUE BOROUGH, PENNSYLVANIA; SOPHIA C. WEAVER AND FIDELITY TITLE AND TRUST COMPANY ADMINISTRATORS OF THE SAID FRANK S. WEAVER, DECEASED, ASSIGNORS, BY MESNE ASSIGNMENTS, TO DEFINANCE SALES CORPORATION.

SPONGE CUP.

Application filed December 1, 1922. Serial No. 604,298.

To all whom it may concern:

Be it known that I, FRANK S. WEAVER, a citizen of the United States, and residing in the borough of Bellevue, in the county 5 of Allegheny and State of Pennsylvania, have invented or discovered the new, useful, and Improved Sponge Cup, of which the following is a specification.

My invention consists in a new and improved cup or container for desk sponges, such as are used in business offices, banks, etc.

The object which I have in view is the provision of a cup or container for such 15 purposes, which will maintain the sponge in a properly moist condition without permitting it to become soggy, ill-smelling or moldy, which will prevent the water from overflowing from the cup onto the desk, 20 counter or papers, when the sponge is pressed with the fingers, and which will contain a larger volume of water proportionate to the mass of the sponge than the cups now in use.

For this purpose I provide a cup, preferably of glass or some other material which may be cheaply formed to shape, having the inner surface of its circumferential wall 25 vertically fluted, as by the provision of alternate ribs and troughs or depressions.

I also provide the interior bottom of the cup with means, such as horizontally disposed ribs, for instance the cruciform rib shown, to elevate the sponge above the bottom proper.

In the accompanying drawings, Fig. 1 is an elevation of a sponge container embodying the principles of my invention; Fig. 2 is a diametric section of the same, 40 and Fig. 3 is a plan view of the same.

The following is a detailed description of the drawings.

A represents the container which may be cheaply pressed or molded of glass or any 45 other suitable material.

The circumferential wall 1 of the container has its inner surface vertically fluted, as by the provision of the vertically disposed ribs 2 spaced apart to form the vertically disposed troughs or channels 3 open to the interior of the cup, said ribs and channels extending to the bottom 4 of the container. The upper extremities of the

ribs 2 are bevelled outwardly to produce a rounded edge, as shown at 5.

The bottom or floor 4 of the container is provided with means for holding the sponge up out of contact with the floor 4. This is preferably accomplished by forming integral ribs, horizontally disposed on the floor. 60 Thus I show the cruciform rib 6.

When the sponge is placed in the container, it is held in place by the vertical ribs 2, leaving the channels 3 open, and the sponge is supported by the rib 6 above the 65 floor of the container.

It is quite evident that space is thus provided for a much greater quantity of water than is possible in a container having a plain inner wall surface with which the 70 sponge is in continuous contact, or wherein the sponge rests flat on the bottom or floor of the container. Thus my container requires replenishment with water at less frequent intervals. Moreover the water standing in the vertical channels has free access to the sides of the sponge, thus maintaining the sponge in a more uniformly moist condition. The bottom of the container, being 75 unoccupied by the sponge furnishes a supply of water which will be naturally drawn up into the sponge and thus prevent its becoming too dry, and which will furnish a supply of water which will be taken up by the sponge when it is pressed down when being used for moistening purposes. If the sponge were permitted to sit flat on the bottom, this portion of the water would enter the substance of the sponge, and soon render 80 it soggy, and soon cause it to become moldy or ill-smelling.

The vertical channels in the wall of the container furnishes proper ventilation for the sponge, so that an unsanitary condition 85 cannot occur.

When the container is well supplied with water, and the sponge is compressed downward with considerable pressure, there will be no overflowing of the water from the container because the water escaping from the top of the sponge, instead of flowing over the sides of the container, will flow down the channels 3 inside the container to the bottom of the latter to replenish the moisture of the sponge when it is released from 100 pressure.

It is therefore not necessary to use care when the sponge is compressed or pressed down upon, since what would be disastrous carelessness in the case of the form of container now in general use, in the case of my improved container results in no overflowing of water from the container.

What I desire to claim is:

1. A container for a desk sponge of cup like form having its floor provided with ribs to elevate the sponge out of contact with the floor of the container.
2. A container for a desk sponge of cup like form having its floor provided with horizontally disposed ribs to elevate the sponge out of contact with the floor of the container.
3. A container for a desk sponge of cup like form having the inner surface of its circumferential wall provided with vertically disposed flutings extending from top

to bottom and having its floor provided with ribs to elevate the sponge out of contact with the floor of the container.

4. A container for a desk sponge of cup like form having the inner surface of its circumferential wall provided with vertically disposed channels running from top to bottom, and having its bottom provided with ribs to elevate the sponge out of contact with said bottom.

5. A container for a desk sponge of cup like form having the inner surface of its circumferential wall provided with vertically disposed ribs extending from top to bottom, said ribs being spaced apart to form interposed channels, and having its bottom provided with ribs to elevate the sponge out of contact with said bottom.

Signed at Pittsburgh, Pa., this 28th day of November, 1922.

FRANK S. WEAVER.
